UNITED STATES PATENT OFFICE.

GOODRICH Q. LEWIS, OF WHEATON, ILLINOIS, ASSIGNOR TO WILLIAM H. MINER, OF CHAZY, NEW YORK.

RAILWAY-CAR DRAFT-RIGGING.

1,290,255.

Specification of Letters Patent.

Patented Jan. 7, 1919.

Application filed April 13, 1916. Serial No. 90,842.

To all whom it may concern:

Be it known that I, GOODRICH Q. LEWIS, a citizen of the United States, residing at Wheaton, in the county of DuPage and State 5 of Illinois, have invented a certain new and useful Improvement in Railway-Car Draft-Rigging, of which the following is a full, clear, concise, and exact description, reference being had to the accompanying drawings, forming a part of this specification.

This invention relates to improvements in railway car draft riggings.

The object of the invention is to provide a draft rigging for railway cars so arranged 15 as to permit removal of the gear from the under side of the sills without disconnecting the yoke and draw bar; to provide an arrangement whereby the draft or center sills are effectively tied against spreading; to 20 dispose the metal in the stops in the most efficient manner to resist the shocks imposed thereon; to provide a novel stop casting having a large riveting area; and to so arrange the stop casting that the coupler key is relieved of the necessity of supporting the 25 coupler and the coupler maintained in proper alinement with the gear.

The invention furthermore consists in the improvements in the parts and devices and 30 in the novel combinations of the parts and devices herein shown, described and claimed.

In the drawing forming a part of this specification, Figure 1 is a central longitudinal vertical section of a draft rigging 35 showing my improvements in connection therewith. Fig. 2 is a horizontal sectional view taken substantially on the line 2-2 of Fig. 1. And Fig. 3 is a vertical transverse sectional view taken substantially on the line 40 3-3 of Fig. 1.

In said drawing, 10 10 denote channel shaped sills or draft members having the flanges thereof turned outwardly, and 11 a rear abutment block or filler extending between and secured to the sills. The shock 45 absorbing mechanism A illustrated in the drawing is that of a well known friction gear of the Miner type, and is operatively connected with the draw bar 12 by means of a horizontal yoke 13, a coupler key 14, the latter extending through elongated slots in the arms of the yoke and corresponding slots in the center sills and stop casting, hereinafter 50 described. As appears from Fig. 1, the yoke 55 is provided with a filler 15 at its rear end,

and the yoke abuts the stop casting 11 which acts as the rear stop for the draft gear in buffing movements.

The front stop members of the rigging are formed by a hollow, substantially rectangular casting B. The casting B comprises vertical side walls 16 16, fitting against and riveted to the center sills, a horizontal upper web 17 extending between said walls 16, a lower horizontal web 18 also extending between said side walls 16 and laterally extended flanges 19 19, at the bottom of the casting B, said flanges 19 19 being riveted or otherwise suitably secured to the lower flanges of the sills. At its rear edge the 60 upper flange 17 is provided with a vertically extending shoulder 20, which goes from sill to sill, and against which the upper portion of the front follower 21 abuts in normal position of the parts. The lower web 18 of the 65 casting B is provided with a downwardly extending flange 22 at its rear end, which also extends entirely across the space between the sills, and forms an abutment for the lower portion of the follower 21. The upper 70 web 17 at its front end is provided with a vertically extending flange 23 against which is secured the buffer casting 24. The lower 75 horizontal web of the casting B is extended forwardly beneath the buffer casting 24, as 80 are also the side walls 16 16, and at its front edge is provided with a depending flange 25. Suitable longitudinally arranged vertical flanges 25, 26, and 27, are provided 85 to brace the flanges 20, and 22 substantially 90 at the center thereof; see Fig. 3. The side walls 16 16 are provided with elongated slots 28 28 to accommodate the coupler key in its forward and rearward movements, as clearly appears from Fig. 2. To the side 95 walls of the casting B, near the front thereof, are bolted blocks 29 29 to form the necessary standard clearance between the draw bar shank and the sills. As clearly appears 100 from Fig. 2, the front ends of the arms of the yoke are provided with reinforcing flanges 30 to form a wider bearing for the coupler key, and the draw bar is similarly reinforced as indicated at 31 to form a wider bearing for the rear side of the coupler key. 105 The gear is supported by means of a detachable saddle plate 32 upon which the combined friction shell and spring casing slides back and forth.

In buffing movement, it is apparent that 110

the draw bar will directly abut the front follower 21 and force the same rearwardly, thus actuating the friction mechanism, the friction shell and spring casing being prevented from rearward movement by the yoke and rear stop 11. In draft, the front follower 21 will bear against the shoulders 20 and 22, thus holding the wedge of the friction mechanism stationary while the shell 10 and shoes move forwardly. In this latter action it will be noted that the forces are transmitted to the stop casting B in the most efficient manner, that is, longitudinally and directly in line with the horizontally 15 disposed webs 17 and 18. The upper face of the lower web 18 is slightly recessed, as indicated at 33, so that the butt of the draw bar may ride back and forth thereon, thus supporting the draw bar directly by the casting B and always maintaining it in the line 20 of draft. As shown, the front follower 21 is recessed on its sides, as indicated at 34 34, to accommodate the arms of the yoke so that the follower is supported by the yoke, thereby 25 eliminating the necessity of an additional supporting plate for the follower.

I claim:

1. As an article of manufacture, a front stop casting for draft riggings, said stop 30 casting comprising integral upper and lower horizontally extending webs provided with

vertical shoulders along their rear edges, the upper web being shorter than the lower web and the latter being adapted to extend to the end of the car, the upper web being adapted 35 to have a buffer block applied in line therewith, said casting having vertical side webs connecting said upper and lower webs.

2. In a draft rigging, the combination with metal draft sills having outwardly extended flanges along their lower edges, of a rear stop casting extending between and secured to said sills, shock absorbing means, yoke-acting means, a draw bar, connections between said yoke-acting means and the 40 draw bar, and a front stop casting for the shock absorbing means, said front stop casting being of hollow rectangular formation with integral side walls and upper and lower horizontal walls, said side walls being secured to the vertical portions of said sills, the upper horizontal wall of said front stop casting being of lesser length than the lower wall to thereby permit the employment of a buffer block in line with said upper horizontal wall, said lower wall being adapted to 45 act as a carry iron for the draw bar.

In witness that I claim the foregoing I have hereunto subscribed my name this 14th day of March, 1916.

GOODRICH Q. LEWIS.
